UNITED STATES PATENT OFFICE.

NACLE F. FORZLY, OF NEW YORK, N. Y.

BUTTONHOOK.

1,425,760.

Specification of Letters Patent. Patented Aug. 15, 1922.

Application filed May 15, 1922. Serial No. 561,124.

To all whom it may concern:

Be it known that I, NACLE F. FORZLY, a citizen of the United States, residing at New York, in the county of New York and State 5 of New York, have invented certain new and useful Improvements in a Buttonhook, of which the following is a specification.

This invention relates to button-hooks, 10 such as are used in buttoning gloves, shoes, or other articles of wearing apparel, and it has for an object to provide a simple, efficient and cheap device which permits of more easy buttoning of the glove or other article, 15 ensuring against slipping and eliminating the double motion necessitated by the use of the ordinary button hook.

For further comprehension of the invention, and of the objects and advantages 20 thereof, reference will be had to the following description and accompanying drawings, and to the appended claims in which the various novel features of the invention are more particularly set forth.

25 Fig. 1 of the drawings is a detail perspective view of my improved button-hook.

Fig. 2 is a similar view of a modified form.

Fig. 3 is a central longitudinal section.

30 Fig. 4 is an end view.

Fig. 5 is a perspective view showing the manner of use of my improved button-hook.

As here embodied my improved buttonhook comprises a tapering shank 10 of channeled cross section and which may be formed 35 of sheet metal suitably pressed to shape, and having a flat handle element 11 into which the smaller end merges.

The larger end of the shank is of approximately semi-circular cross section, but with 40 the sides thereof slightly extended tangentially to deepen the channel, this end being of sufficient diameter to engage over the button to be fastened. Formed on the said 45 larger end of the shank, are a number of prongs or lugs of which there is a pair of side ones 12, and an intermediate one 18, and which are adapted to engage under the button. The prongs 12 are spaced apart at 50 their inner ends a sufficient distance to allow the fastening threads of the button to pass therebetween, and are of less depth, vertically of the channel, than the latter, being

flush on their upper edges with the sides of the channel. 55

In the modification shown in Figs. 2 to 4 I show the shank 10 as having a pair of fixed prongs 12' and a central adjustable prong 18. As here shown a flat bar 15 is mounted in the channeled shank 10 and is 60 formed with a longitudinal slot 16 through which project a pair of headed studs 17 fixed in the shank 10, these studs engaging the bar 15 with sufficient frictional force to hold it in adjusted positions. Upon the forward 65 end of the bar 15 is a laterally projected prong 18 which is turned inwardly across the channeled shank and evenly spaced between the two prongs 12'. The bar 15 may be provided on its rear end with a lug 19 70 for convenience in grasping. When a glove is to be buttoned the bar 15 is pushed forward until the rear stud 17 strikes the rear end of slot 16, in which position the prong 18 lies in a common plane with the prongs 12', 75 and engages between the different reaches of the thread which secures the button in place, this being the position shown in Fig. 3. When a shoe is to be buttoned the bar 80 is pulled backward to the position shown in Figs. 1 and 2.

In Fig. 5 I have illustrated the manner of use of my improved device in buttoning a shoe, it being understood that it is applied in a similar manner in buttoning a glove. 85 In applying the hook, the same is inserted, small end first, through the button hole in an outward direction and the pronged end engaged with the button. The shank 10 is then swung in a direction to draw the button and button hole into registry, the edges of the button hole finally slipping over the end of the shank, and consequently over the button, which is thus buttoned by a single 90 swinging movement of the shank in a single 95 plane.

Having thus described my invention what I claim as new and desire to protect by Letters Patent of the United States is as follows:

1. A button-hook comprising a channeled shank having three transversely spaced in-turned prongs at the end thereof, the center one of said prongs being removable from operative relation with respect to the 105 other two.

2. A button-hook comprising a shank of channelled cross section at one end and tapering to a flat cross section at its other end, a pair of fixed inturned prongs at opposite sides of the large end of the shank, and a third removable prong arranged between the other prongs.

3. A button-hook comprising a shank of channelled cross section at one end and tapering to a flat cross section at its other end, a pair of fixed inturned prongs at opposite sides of the large end of the shank, and a third removable prong arranged between the other prongs, said last prong being slideable longitudinally of the shank.

4. A button-hook comprising a channelled shank having at opposite sides of one end a pair of fixed inturned prongs, a bar slideable

on said shank, a third prong carried by said bar, and means limiting sliding movement of said bar in a forward direction when the third prong lines in a common plane with the said pair of prongs.

5. A button-hook comprising a shank of channelled cross section at one end and tapering to a flat cross section at its other end, a pair of fixed inturned prongs at opposite sides of the large end of the shank, a longitudinally slotted bar in said shank, a pair of headed studs fixed in said shank and passing through the slot in said bar and frictionally engaging the latter, and a third prong on the forward end of said bar.

In testimony whereof I have affixed my signature.

NACLE F. FORZLY.
